LABELING DEVICE FOR LOOSE LEAF
BINDERS

Harold C. Peterson, Belleville, N. J., and Felix A. Ganteaume, Brooklyn, N. Y.

Application March 30, 1933, Serial No. 663,480

6 Claims. (Cl. 129—1)

The present invention relates to means for securing a label or legend to the edges of a pile of loose leaves which are held together by engagement of the leaves with a post or posts passing through them.

More particularly the invention relates to the securing of a label, index or the like to the open back of a loose leaf binder consisting of a pile of leaves having openings through which pass 10 posts and having upon each side of the pile a cover, the covers and leaves being clamped together by screw means applied to the posts.

It will readily be seen that the usual labels or indexes cannot be applied to the edges of the 15 leaves at the open back of the loose leaf binder in the manner that they are applied to the back of ordinary books, and the difficulties in the way of applying labels to the edges of the leaves at the open back of a loose leaf binder have, as a 20 general rule, prevented the use of labels in that position. It is commonly the practice to apply the identifying labels to the loose leaf binders upon the covers. The ordinary manner of storing books is on edge with the backs outward. 25 With the labels placed as just specified it is impossible to identify any binder by running the eye along the indexes as is usual with ordinary books, but it is necessary to pull each binder out of position sufficiently so that the label on its 30 side may be viewed. This is an inconvenient and time-consuming operation, and the main object of the invention is to provide, by improved means, the securing of a label on the edges of the loose leaves at the open back of a loose leaf binder.

35 A further object of the invention is to provide a labeling means of the character as indicated which shall be readily attached or detached in a simple manner and with minimum care on the part of the user and which shall be securely held 40 in position.

A further object of the present invention is to provide a label device at the open back of a loose leaf binder which shall remain in place at all times whether the leaves are clamped together or not.

45 A further object of the invention is to provide a device of the character described wherein the labeling means will fit snugly to the sheet edges at the back of the book regardless of lack of uniformity of the punchings in the sheets or wearing of the holes in the sheets against the posts.

50 It is a further object of the invention to provide a labeling device for the open back of a

loose leaf binder which shall be applicable regardless of the number of posts employed.

A further object of the invention is to provide a labeling device which shall lie within the ends of the cover projecting beyond the edges of the 60 loose leaves at the back whereby the binder being placed upon its back on a table, desk or the like, will rest upon the covers and the labeling device will be held out of contact with the supporting surface so that it cannot scratch such surface. 65

A further object of the invention is to provide a labeling device for the open back of a loose leaf binder which shall be strong and shall be resilient where necessary to cause close fitting and of stiff and unyielding construction where such characteristic is required. 70

A further object of the invention is to construct the labeling device for attachment to the open back of a loose leaf binder of a single piece 75 of sheet metal.

A further object of the invention is to provide labeling device to be applied to the open end of a loose leaf binder, which device shall comprise a holder for a label card or cards, said card or cards being readily insertable and removable at 80 appropriate times but securely held in said holder when in use on the back of the binder.

Other and ancillary objects of the invention will appear hereinafter.

In the accompanying drawing which illustrate 85 the invention—

Fig. 1 is a perspective view of a loose-leaf binder with the improved labeling device applied thereto;

Fig. 2 is a top plan view, on an enlarged scale, 90 of the rear end of the loose-leaf binder as shown in Fig. 1, the front portion of the loose-leaf binder being broken away, and the view being also broken away to show a section through the post to which the labeling device is applied;

Fig. 3 is a front elevation of the labeling device on the same scale as Fig. 2;

Fig. 4 is a section on the line 4—4 of Fig. 3;

Fig. 5 is a section on the line 5—5 of Fig. 3;

Fig. 6 is a perspective view, on an enlarged 100 scale, of a fragment of the labeling device; and

Fig. 7 is a plan view of a sheet metal blank from which the labeling device is formed.

Referring to the drawing, the loose-leaf binder comprises the usual covers 1 between which extend the posts 2 which extend through perforations in the loose leaves 3 between the covers, the posts serving to clamp the covers and leaves tightly together or to be loosened so that the leaves may be disengaged from the posts or others 105 110

inserted in position as may be desired. Such loose leaf binders are well known and require no further description.

The labeling device comprises a label portion 5 adapted to lie against the back edges of the loose leaves of the book. This label portion comprises a front plate 4 having a window 5 and a back plate 6 having its bottom integrally joined to the front plate 4. Extending rearwardly from the 10 front plate 4 are the side portions 7 and 8 which are bent inwardly at the rear at 9 and 10 to overlap the back plate 6. There is thus formed a pocket having the front and back plates 4 and 6 and sides 7 and 8, within which may be inserted 15 an index or label card 11 which may carry the title of the book or advertising matter or any desired notation. In front of the index card may be placed a transparent plate 12 of celluloid or other suitable material through which the notations on the index card may be viewed. This 20 transparent plate may be colored or otherwise conditioned so as to form an additional indication of the status of the book or convey other desired information as, for instance, the transparent plates used on the books containing records for a given year, may have one color, as for instance green, while the transparent plates of the labeling device on books for another year, 25 may have a different color, as for instance red, and so on for any number of years, a different color being provided for each respective year, so that the books for a given year may be identified by the color.

The edges of the window 5 are bent inwardly 30 as shown so that the outer surface is smooth and not sharp, so that they will not be liable to catch in clothing or other articles with which they may come in contact.

The back plate 6 has at its top edge ears 13 35 which are bent rearwardly and downwardly tightly about the parts 9 and 10. This serves to stiffen the structure and render it more rugged and also serves to hold the back plate 6 spaced from the front plate 4 so that the cards may freely move 40 between these plates in the pocket or holder of which they form a part. Slits are cut from the top downwardly in the back plate 6 to form the spring tongue 14, the bead 15 being provided 45 near the base of and extending transversely of the tongue to improve its spring action. The 50 spring 14, tending to stand away from the front plate (see Fig. 4), has at its upper edge a forwardly extending lip 16 adapted, when the spring 55 is pressed toward the plate, to cooperate with a rearwardly extending lip 17 on the plate 4 to close the top of the index card holder and prevent removal of the index cards therefrom.

Joined to the parts 9 and 10 and extending 60 rearwardly from the plate-like index carrier are two flat plate-like projections 18 and 19. Each 65 of these projections has a recess or slot 20 opening at a lateral side of the rearwardly projecting plate and forming a hook 21 adapted to hook over one of the binder posts 2 and secure the 70 labeling device in position. The edge 22 of the slot 20 which is furthest from the label or index holder has its edge serrated as shown, the notches of the serrations being such as to approximately conform to the periphery of the binding post. 75 Also the lower end of the serrated edge is at a greater distance from the index or label holding plate than is the top portion of said edge. In other words the serrated edge is tapered away from the index or label holder proceeding from the closed end of the recess to the open end.

The labeling device may be constructed from a flat sheet metal blank, as shown in Fig. 7, having the various parts corresponding to the parts of the plate holder, similar parts being indicated by the same reference characters.

In placing the labeling device in use, the leaves are loosened sufficiently so that the projections 18 and 19 may be inserted between them at appropriate points. The projections are then inserted between the leaves and the hook portions 21 hooked over a binding post 2 so that the binding post enters the recesses or slot 20. The device is then pressed downwardly when the tapered serrated edge of the recess will force the label holder against the back edges of the leaves and the downward pressure is continued until the label holder is forced tightly against the leaf edges. The labeling device is secured in this position by the engagement of the binding post in one of the serrations. The operation of tightly forcing the label holder against the edges of the leaves causes the leaves to push the spring 14 towards the label holder thereby securing the index or label cards in the holder pocket and also the spring action of the tongue 14 against the leaves draws the hook portion 21 forwardly so as to hold the serrated edge securely in engagement with the post.

The improved labeling device has the advantage that it engages with but a single binding post so that it may be applied to any binder no matter what the spacing between the posts. Also the characteristic of forcing the holder inwardly by pressing the device downwardly insures that it will be held tightly against the edges of the leaves regardless of whether or not the leaves are uniformly punched and regardless of whatever the distance may be between the post and the adjacent edges of the leaves. Also it will be apparent that the use and securing of the device is independent of whether or not the leaves are clamped together as it will function as well when the leaves are placed loosely together as when they are tightly clamped. The invention also has many other advantages.

While the invention has been illustrated in what is considered its best application it may have other embodiments without departing from its spirit and is not therefore limited to the structure shown in the drawing.

What we claim is:

1. A labeling device for a loose leaf book having one or more posts extending through the leaves, comprising a label holder adapted to lie against the edges of the leaves and a projection 130 extending therefrom adapted to enter between the leaves, said projection having a single post-embracing slot extending longitudinally of the leaf edges against which the said holder is adapted to lie and having an open end, the said slot 135 being wider at its open than at its other end.

2. A labeling device for a loose leaf book having one or more posts extending through the leaves, comprising a label holder adapted to lie against the edges of the leaves and a projection extending therefrom adapted to enter between the leaves, said project having a single post-embracing slot extending longitudinally of the leaf edges against which the said holder is adapted to lie and having an open end, said slot having a 145 serrated edge.

3. A labeling device for a loose leaf book having one or more posts extending through the leaves, comprising a label holder adapted to lie against the edges of the leaves and a projection 150

- extending therefrom adapted to enter between the leaves, said projection having a single post-embracing slot extending longitudinally of the leaf edges against which the said holder is adapted to lie and having an open end and spring means for drawing the edge of said slot against its embraced post. 5
4. A labeling device for a loose leaf book having one or more posts extending through the leaves, comprising a label holder adapted to lie against the edges of the leaves and a projection extending therefrom adapted to enter between the leaves, said projection having a single post-embracing slot extending longitudinally of the leaf edges against which the said holder is adapted to lie and having an open end, said slot having a serrated edge and spring means for drawing the said serrated edge against the embraced post. 10
5. A labeling device for a loose leaf book having one or more posts extending through the leaves, comprising a label holder adapted to lie against the edges of the leaves and a projection extending therefrom adapted to enter between the leaves, said projection having a single post-embracing slot extending longitudinally of the leaf edges against which the said holder is adapted to lie and having an open end, the edge of said recess engaging with said post being tapered to different distances from the holder whereby, as the labeling device is placed in position on the book, the said holder will be forced against the leaf edges. 15
- the leaves, said projection having a single post-embracing slot extending longitudinally of the leaf edges against which the said holder is adapted to lie and having an open end, said slot having a serrated edge, the serrated edge of said slot being at a greater distance from the label holder at its open than at its closed end. 20
6. A labeling device for a loose leaf book having one or more posts extending through the leaves, comprising a label holder adapted to lie against the edges of the leaves and a projection extending therefrom adapted to enter between the leaves, said projection having a single post-embracing slot extending longitudinally of the leaf edges against which the said holder is adapted to lie and having an open end, the edge of said recess engaging with said post being tapered to different distances from the holder whereby, as the labeling device is placed in position on the book, the said holder will be forced against the leaf edges. 25
